UNITED STATES PATENT OFFICE.

ARTHUR H. FOWLER, OF PHILADELPHIA, PENNSYLVANIA, ASSIGNOR TO THE FOWLER & WOLFE MANUFACTURING COMPANY, OF PENNSYLVANIA.

DESIGN FOR A RADIATOR-SECTION.

SPECIFICATION forming part of Design No. 28,760, dated May 31, 1898.

Application filed December 15, 1897. Serial No. 662,085. Term of patent 14 years.

To all whom it may concern:

Be it known that I, ARTHUR H. FOWLER, of the city and county of Philadelphia and State of Pennsylvania, have invented a new and original Design for Radiator-Sections, of which the following is a specification.

My design for radiator-sections is illustrated in the accompanying drawing, which shows a perspective view of a radiator-section embodying my design.

The design consists in the conformation or shape of the radiator-section.

The section consists of a quadrilateral shape, composed of outer tubular portions A A and B B, connected together at the corners, and a series of intermediate tubular portions C C between the outer portions B B, with a series of small tubular portions D be-

tween the intermediate tubular portions C and the outer portions A A and the adjacent intermediate portions C, respectively. The corners of the sections where the tubular portions A A and B B are united are formed with enlargements or heads E.

What I claim as new, and desire to secure by Letters Patent, is as follows:

The design for a radiator-section consisting of a flat section having the shape or conformation substantially as described and shown.

In testimony of which invention I hereunto set my hand.

ARTHUR H. FOWLER.
